Patented May 5, 1970

217,442

COMBINED PANEL AND MOLDING ASSEMBLY

Vernon H. Jones, Cuyahoga Falls, Ohio
(2553 Falmouth Road, Akron, Ohio 44313)

Filed Jan. 22, 1969, Ser. No. 15,452

Term of patent 14 years

Int. Cl. D25—01

U.S. Cl. D13—1

FIG. 2

FIG. 3

FIG. 4

FIG. 1 is a front view of a combined panel and molding assembly, it being understood that the portion shown in full lines is repeated in the portion shown in broken lines;

FIG. 2 is an enlarged fragmentary front view of a portion of the combined panel and molding assembly shown in FIG. 1;

FIG. 3 is a fragmentary perspective view showing the corner of FIG. 2; and

FIG. 4 is a cross sectional view taken at 4-4 of FIG. 2.

The rear of the article is plain with no ornamentation.
I claim:

The ornamental design for a combined panel and molding assembly, as shown and described.
